HAIR CURLER PIN

Arthur H. Madore, Los Angeles, Calif.

Application April 22, 1957, Serial No. 654,395

5 Claims. (Cl. 132—37)

This invention relates to pins for holding wrappings of hair on tubular hair curlers.

A pin of this type, as heretofore provided, has a pair of opposed clamping legs one of which is adapted to be disposed within the bore of the tubular hair curler so that the other leg will overlie and hold the wrapping of hair on the curler. Such a pin is subject to dislodgment or slipping objectionably relative to the curler, inasmuch as only the engagement of the legs with the hair and the curler respectively, is relied upon to hold the pins in place. Moreover difficulty is sometimes experienced in mounting such a pin in proper position on the curler with the quickness and ease that is desired.

It is an object of the present invention to provide an improved pin of the character described which eliminates the objections above noted and provides for a quick and easy application of the pin to the curler in a manner assuring that the pin will remain in the proper position.

It is another object of this invention to provide a pin of the character described having novel means between and apart from the legs thereof for gripping the curler to securely hold the pin in place.

A further object is to provide a pin such as described wherein the juncture portion of the legs is formed with a slot or notch to define opposed portions for gripping the inner and outer surfaces of the tubular curler at one end of the curler, to assure that the pin will remain in place.

Another object is the provision of a curler such as described, in which one of the legs thereof adjacent its free end, is formed to grip the inner surface of the curler between the curler ends, so that in cooperation with means at the juncture of the legs for gripping an end of the curler, the pin will be reliably held against dislodgment and objectionable slipping.

An additional object is to provide a pin of the character described wherein one leg is shorter than the other and of less length than the tubular curler. This facilitates application of the pin to the curler also makes it possible for a portion of the shorter leg spaced from the juncture of the legs, to be forcibly engaged with the interior surface of the tubular curler between the ends of the latter, while means at the juncture portion grips the inner and outer surfaces of the curler at one end of the curler.

Another object of this invention is to provide a pin such as described wherein each of the opposed legs is curved so as to be outwardly bowed whereby the legs will converge toward the free ends thereof and the resultant space between the legs will provide for an easy application of the pin and accommodate the desired amount of hair wound on the curler.

It is another object to provide a pin such as described wherein the juncture portion of the legs serves as a handle or gripping portion and makes it possible to provide novel means for gripping an end of the tubular curler.

This invention possesses many other advantages and has other objects which may be made more easily apparent from a consideration of the embodiment of the invention shown in the drawing accompanying and form-

2

ing part of the present specification. This form will now be described in detail, illustrating the general principles of the invention; but it is to be understood that this detailed description is not to be taken in a limiting sense, since the scope of the invention is best defined by the appended claims.

Referring to the drawing:

Fig. 1 is a perspective view of a pin embodying the present invention;

Fig. 2 is a side elevation of the pin and a tubular hair curler with the latter having a wrapping of hair thereon, showing how the pin is applied to the curler;

Fig. 3 is a side elevation of the pin as it would appear when properly positioned in accordance with this invention, on a tubular hair curler having a wrapping of hair thereon, the curler being shown in longitudinal section; and

Fig. 4 is a cross-sectional view taken on the line 4—4 of Fig. 3.

Referring more specifically to the accompanying drawing, it will be seen that a curler pin embodying the present invention generally includes a pair of opposed clamping legs 1 and 2, each joined to the other at one end by means of a juncture portion 3. The pin may be made of any suitable material and readily lends itself to being made in one piece of plastic material. Preferably the material used in such that the legs 1 and 2 will be somewhat resilient to provide a clamping action thereof.

The pin is adapted for use with any type of tubular hair curler, for example, the perforated curler 4 here shown and on which hair to be curled may be wound as at 5.

The length of the legs 1 and 2 is determined by the length of the curler, it being preferable that the legs do not exceed the length of the curler. It is also preferable to have one of the legs, for example, the leg 1, shorter than the other leg. With this arrangement, the shorter leg 1 may be positioned within the tubular curler 4 with a portion thereof, for example the end portion 6, arranged to resiliently press against the inner surface of the curler between the ends of the latter, while the longer leg 2 embraces the wrapping 5 of hair to hold the hair in place. These relative lengths also facilitate the application of the pin to the curler as will be apparent with reference to Fig. 2.

In accordance with this invention, means are provided to grip the curler 4 so that the clamping or gripping action of the legs 1 and 2 alone, need be depended upon to hold the pin in place. Accordingly the pin is formed so that means are provided between and apart from the legs, to grip the inner and outer surfaces of the curler at one end of the curler. As here shown, this means is embodied in the juncture portion 3 of the pin in the form of a slot or notch 7 which defines opposed gripping portions or surfaces 8. The gripping surfaces 8 extend in the direction of the length of the legs 1 and 2, being spaced one from the other a distance less than the spacing of the legs at the juncture portion 3. In other words, the width of the slot 7 is less than the space between the legs 1 and 2 at the joint thereof with the portion 3. This construction forms shoulders on opposite sides of the mouth of the slot 7, the shoulders extending from the slot mouth to the points where the legs join the portion 3. The shoulder between the longer leg 2 and the mouth of the slot 7 as shown in Fig. 3, acts as a stop to prevent hair from getting into the slot or from sliding off the end of the curler. The two shoulders act as guides in causing an edge of the curler to be engaged in the slot 7. The width of the slot or notch 7 is somewhat less than the thickness of the wall of the tubular curler 4 so that when the pin is positioned on the

50

65
70

curler, the edge of the curler at the end of the curler opposed to the slot 7, may be forced or wedged into the slot, whereby the gripping surfaces 8 will frictionally grip the inner and outer surfaces of the curler. This will provide for a reliable holding of the pin on the curler, as the holding action of the legs 1 and 2 especially the leg 1 at the end portion 6, together with the holding action of the surfaces 8, assures that the pin will remain in proper position. However, the pin readily may be removed when this is necessary.

It should be noted that it is preferred to make the legs 1 and 2 somewhat arcuate so that they will bow outwardly between their ends to accommodate the desired amount of hair. This arrangement also causes the legs to converge toward their free ends, but so that a space is left between these ends to facilitate a quick and easy application of the pin to the curler as shown in Fig. 2.

It has been found that by serrating or notching the inner surface of the longer leg 2 as at 9, the hair is held in evenly wound position, the pin is more securely held on the hair and better ventilation of the hair is provided for a quick drying of the hair.

The holding of the pin and manipulation thereof is facilitated by providing roughened gripping surfaces 10 on opposite sides of the flat juncture portion 3. This juncture portion forms a comparatively wide gripping member of greater width transversely and longitudinally than the diameter of either leg. As a result of this formation, the pin may be easily handled, is not weakened by the slot 7 formed centrally of the juncture portion and a strong and durable joint of the legs is provided.

Where the tubular curler is made of somewhat compressible and resilient material, such as rubber, synthetic rubber or some plastic material having these characteristics, it is apparent that the expansion action and resilience of such material will enhance holding action of the gripping surfaces 8 formed by the slot 7 in the juncture portion 3 of the pin.

The free ends of the legs 1 and 2 may be beveled or slightly rounded somewhat and slightly outwardly flared so that the pin may be quickly and easily applied to the curler.

It is important to emphasize the advantages derived in having one leg of the pin shorter than the other leg and in providing the gripping or "locking" means at the juncture of these legs. With reference to Fig. 2, it will be seen that the longer leg 2 quickly and easily may be positioned on the hair wrapping 5 so that thereafter, the pin quickly and easily may be pushed into place on the curler. In this operation the longer leg 2 acts as a guide assuring that the short leg 1 will enter the bore of the curler as the long leg 2 slides into position to hold the hair on the curler.

The user may, in one operation, quickly and easily mount the pin on the curler and thereafter as easily "lock" the pin against displacement, by further pushing the pin against the curler so that an end portion of the curler will enter the slot 7 and be frictionally held between the gripping surfaces 8 as shown in Fig. 3. In this "locking" or gripping operation, the legs 1 and 2 guide an end portion of the curler into the slot 7.

It should be noted that the free end portion of the legs 1 and 2 and the notch or slot 7, provide a three point gripping and holding action assuring that the pin will remain in place. Moreover these legs provide a larger-than-usual hair accommodating space between the longer leg 2 and the curler. This increased hair accommodating space is provided by the particular manner in which the legs are bowed outwardly so as to be subject to contact with the curler only at the free end portions of the legs. In this connection it will be observed that it is the pronounced bowing of the shorter leg 1 which makes possible the desired hair accommodating space more particularly than the bowing of the longer leg 2. This

longer leg is substantially straight for the major portion of its length, the outward bowing being adjacent the free end portion thereof. With this arrangement, the substantially straight portion of the leg 2 will effect the desired uniform pressure and holding action on small wrappings of hair ends on the curler as well as on larger hair wrappings.

I claim:

1. A pin for holding a wrapping of hair on a tubular hair curler comprising a pair of opposed resilient clamping legs; a juncture portion of greater width than the diameter of said legs; said portion having a slot defining opposed portions for gripping the inner and outer surfaces of said curler at one end of the curler; each of said legs being bowed outwardly between its ends, one of said legs being of less length than the other with the free end portion only adapted to press against the inner surface of said curler when said gripping means grips said curler.
2. In a hair curler device comprising: a tubular member adapted to receive thereon a wrapping of hair, a hair pin having a pair of opposed legs and a juncture portion to which each leg is joined at one end; one of said legs being disposed interiorly of the tubular member with the other leg disposed exteriorly of the tubular member, said juncture portion having means for gripping the tubular member; that improvement wherein said juncture portion has a greater width in directions transversely and longitudinally of the pin than the diameter of either leg; and wherein said gripping means is constituted by a pair of gripping surfaces disposed in spaced relation and defining therebetween a slot located solely in said juncture portion.
3. In a pin for holding a wrapping of hair on a tubular hair curler, the pin including a pair of opposed legs and a juncture portion to which each leg is joined at one end; that improvement wherein said juncture portion is a solid body provided substantially centrally thereof with opposed surfaces extending in the direction of the length of said legs and spaced laterally and axially from the inner surfaces of said legs for gripping inner and outer surfaces of said curler to hold the pin thereon.
4. In a pin for holding a wrapping of hair on a tubular hair curler, the pin including a pair of opposed legs and a juncture portion to which each leg is joined at one end; that improvement wherein said juncture portion is of greater width in directions transversely and longitudinally than the diameter of either leg and is provided with opposed surfaces extending into said portion in the direction of the length of said legs; said legs being joined to said juncture portion at points spaced laterally from said opposed surfaces.
5. In a pin for holding a wrapping of hair on a tubular hair curler, the pin including a pair of opposed legs and a juncture portion to which each leg is joined at one end; that improvement wherein said juncture portion comprises a body of greater width in directions transversely and longitudinally than the diameter of either leg and is provided with a slot spaced laterally and axially from the inner surfaces of said legs where the legs are joined to said body; said slot defining opposed surfaces for gripping inner and outer surfaces of one end of the curler; there being shoulders on said body extending from the mouth of said slot to said inner surfaces of said legs where the latter are joined to said body.
